INVENTOR:

FREDERICK M. VENZIE,

BY

William J. Jackson

ATTORNEY.

UNITED STATES PATENT OFFICE

FREDERICK M. VENZIE, OF PHILADELPHIA, PENNSYLVANIA

BUILDING STRUCTURE

Application filed February 29, 1928. Serial No. 257,884.

This invention, generally stated, relates to a building structure and has more especial relation to a floor or like construction of concrete such as is disclosed in my application for 5 Letters Patent Serial No. 75,686, filed December 16, 1925, the present case being for an improved structure.

According to the accepted methods of building concrete floor and like structures prior to 10 my aforesaid invention it was quite difficult and expensive to attach metal lath in place to receive ceiling plaster and usually required the services of skilled mechanics.

The leading object of the present invention 15 is not only to overcome the above described disadvantageous features but provide a novel structure of the character stated over and above my former structure in which a floor or the like is provided combining efficiency, 20 simplicity, cheapness, and saving of time and in which unskilled labor may be successfully employed in the erection of metal lath to receive the ceiling plaster.

Other and further objects not at this time 25 appearing will be hereinafter referred to.

The invention consists of the novel construction hereinafter described and finally claimed.

The nature, characteristic features and 30 scope of the invention will be more fully understood from the following description undertaken in connection with the accompanying drawings forming part hereof, and in which:

Fig. 1, is a fragmentary view in section 35 illustrating a floor structure in accordance with the invention in which the concrete is poured upon the forms.

Fig. 2, is a similar view with the forms 40 removed and the metal lath secured in position for ceiling plaster reception.

Fig. 3, is an enlarged fragmentary view in cross-section of a piece of form having nailed thereupon a metal lath attachment device, 45 prior to pouring of concrete.

Fig. 4, is a similar view illustrating the concrete poured, the form removed and the metal lath in place.

Fig. 5, is a view in plan of one of the metal 50 devices shown in the foregoing figures, and

Fig. 6, is a view in cross-section taken upon the line 6-6 of Fig. 5.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged 55 and organized and that my invention is not limited to the precise arrangement and organization of the instrumentalities as herein shown and described.

In the practice of the present invention the 60 usual forms 1 are erected and supported or shored up by beams 2, as seen in Fig. 1. The next step, as best seen at the right hand side of Fig. 1, is to secure upon the upper faces of the forms 1, a plurality of spaced, metal lath, 65 attachment devices, best seen in Figs. 3 to 6. Each attachment, which is designated 3, is greatly elongated and is composed of thin metal stamped from a single piece of material to a shape which in cross-section is 70 of inverted V-shape, see Fig. 6, and each are secured in inverted position as by a nail 4 to the upper face of a form 1, best seen in Fig. 3. The apex or ridge 5 of each attachment is 75 apertured at 6 for nail reception. The ends 80 of each attachment 3 are inclined outwardly and downwardly as at 7, and terminate in horizontal, flat feet 8 which are broader at their free ends than at that portion of each foot which joins an attachment 3. This 85 provides an efficient, broad, flat surface for abutting upon a form 1 so that in nailing an attachment 3 to place a good tight connection may be effected, whereby when the concrete 9 90 is poured the said attachments will not shift. The acutely disposed, inverted V-shaped walls of an attachment are notched at the bottom as at 10. Extended laterally across an attachment, see Figs. 3, 4, and 5, and engaging 95 opposed notches 10 are wire members 11, the free ends of each being first extended upwardly at 12 over the inclined wall of the attachment, the said ends then being twisted together at 13 and the free ends of the wire members being extended laterally in opposed 100

relation as at 14. The concrete 9 having been poured to form the floor, obviously the metal lath attachments 3 are firmly embedded therein. This position of parts is seen in Fig. 5. 1. With set of concrete 9 obtained, the forms 1 are removed, thus exposing upon the underside of the floor a plurality of spaced attachments 3 with the wire parts 11 extended across each attachment. It is to be understood that with the removal of forms 1 the 10 nails 4 are left hanging within the inverted V-shaped channels of the attachments 3. Metal lath of any desired type, as for example wire mesh 15, is now positioned to receive ceiling plaster 16, see Fig. 2. In securing the wire mesh 15 in place the same is wired as at 16 to the exposed wire members 11 as best seen in Fig. 4. While the above described structure is adapted for any desired form of floor, ceiling or like structure it is especially efficient 20 where ceiling beams are formed, as shown in the drawings, because the metal lath can be stretched taut and very easily wired to the attachments which latter may be positioned 25 upon both side and bottom walls of a beam.

I am aware that the invention may be embodied in other specific forms without departing from the spirit or essential attributes thereof, and I therefore desire the present embodiment to be considered in all respects as 30 illustrative and not restrictive, reference being had to the appended claim rather than to the foregoing description to indicate the scope of the invention.

35 What I claim is:

A metal lath support for concrete construction comprising an elongated, inverted, V-shaped, thin metal device having a continuous upper acute ridge arranged centrally 40 thereof and extending throughout its length, said acute ridge being apertured for the reception of a series of nails, the opposed ends of said device being each outwardly and downwardly inclined, which inclined parts 45 each terminate in an outwardly flaring, flat foot, of a width in excess of the width of said member, the open bottom of which inverted V-shaped device has extended thereacross a wire member the ends 50 of which are extended upwardly around the upper, acute, inclined surface of said device in the shape of a triangle considered in cross section and twisted together with the free ends thereof extended in opposed relation, 55 transversely to the longitudinal axis of said device.

In testimony whereof, I have hereunto signed my name.

FREDERICK M. VENZIE.
